UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,605, dated August 28, 1894.

Application filed August 3, 1894. Serial No. 519,877. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of ornamental scrolls with groups of flowers and leaves attached to said scrolls and placed at uniform distances apart as represented in the accompanying drawing. The border or upper portion of the design is formed of a series of ornamental scrolls interlacing with groups of flowers and leaves above said scrolls as represented in the drawing. 15

What I claim is—

1. The design for wall paper herein shown and described.
2. In the design for wall paper, the border 20 herein shown and described.

Witness my hand this 31st day of July, 1894.

CHARLES BOOZE.
